ELASTIC FLUID PRIME MOVER

Filed July 2, 1926

Inventor:
Nino Hilgers,
by *Alexander S. Hunt*,
His Attorney.

UNITED STATES PATENT OFFICE

NINO HILGERS, OF CHARLOTTENBURG, GERMANY, ASSIGNOR TO GENERAL ELECTRIC COMPANY, A CORPORATION OF NEW YORK

ELASTIC-FLUID PRIME MOVER

Application filed July 2, 1926, Serial No. 120,205, and in Germany July 22, 1925.

The present invention relates to elastic fluid turbines wherein at an intermediate point in the prime mover the elastic fluid is re-heated in order to increase the efficiency 5 of the lower pressure portion of the prime mover.

The object of the invention is to provide an improved means for re-heating, and for a consideration of what I believe to be novel 10 and my invention, attention is directed to the accompanying description and the claims appended thereto.

In the drawing, the figure is a diagrammatic view of an elastic fluid turbine installation 15 embodying the invention and adapted to be operated in accordance with the improved method.

Referring to the drawing, 1 indicates a turbo-generator set comprising a turbine 20 having two high pressure sections 2 and 3 connected in series by a conduit 4. High pressure elastic fluid is supplied to turbine section 2 by a conduit 5 which receives elastic fluid from a battery of boilers 6. 7 indicates a turbo-generator set, the turbine of 25 which comprises two low pressure turbine sections 8 and 9. They receive elastic fluid in parallel from the exhaust end of turbine section 3 through a conduit 10 and they exhaust through conduits 11 to suitable condenser means, not shown. The arrangement so far described is to be taken as typical of 30 any elastic fluid prime mover installation comprising a high pressure portion and a low pressure portion, and wherein it is desired to re-heat the elastic fluid as it flows from the high pressure portion to the low pressure portion.

Now, according to the present invention, 35 instead of re-heating all the elastic fluid to a desired temperature as it flows from the high pressure portion to the low pressure portion of the turbine, a small portion only of the elastic fluid is re-heated. This portion, however, is re-heated to a temperature much 40 higher than the desired re-heat temperature and after being re-heated is returned to the main body of the elastic fluid and mixed therewith so as to bring all the elastic fluid 45 up to a certain desired mean temperature.

In other words, according to the invention, I separate a part of the elastic fluid from the main body of the elastic fluid, convey such part to an intermediate super-heater or re-heater, there impart to such separated part 55 the heat intended for the total elastic fluid and then return such re-heated part to the main body of the elastic fluid. The re-heated part then mingles with the main body of the elastic fluid and imparts some of its heat thereto, with the result that the total elastic fluid is re-heated to a desired temperature.

My invention has the advantage that since 60 only a part of the elastic fluid is led to the intermediate super-heater the latter as well as the branch pipes for conveying the elastic fluid to and from it, may be constructed of 65 smaller dimensions than before. This means that re-heating can be effected much more economically in that the original equipment 70 for the re-heating can be provided at a much smaller cost and in that the pressure losses in the pipes can be kept smaller. This is a very important consideration 75 for heretofore when calculating re-heating for certain installations, it has been found actually that because of the cost of the piping system and the re-heater for conveying and re-heating all the elastic fluid, and the losses incident thereto, the possible 80 gain in economy due to re-heating was offset almost altogether by the interest on the initial investment and the cost of upkeep.

My invention has a further advantage in 85 that it gives increased security of operation because, in the event of a breakdown of the intermediate super-heater, the elastic fluid can be passed directly from the high pressure turbine portion into the low pressure turbine portion without difficulty and without the provisions of special piping arrangement. Also, because of the smaller amount of elastic fluid to be re-heated, the control and operation 90 of the super-heater becomes much simpler than would be the case otherwise.

In carrying out the invention, suitable 95 means may be provided to effect the separation of a definite constant quantity of elastic fluid to be re-heated from the main body of the elastic fluid and also in the branch con-

duits there may be provided a suitable circulating device, such as a pump, to overcome the frictional resistance.

Referring now to the drawing, 12 indicates a branch pipe or conduit for conveying a part of the elastic fluid from conduit 10 to an intermediate super-heater or re-heater 13 located in the boiler means 6. From re-heater 13 a pipe 14 conveys the re-heated elastic fluid back to conduit 10. 15 indicates a pump in pipe 12 which may be utilized to overcome frictional resistance and 16 indicates suitable means which may be adjusted to effect the desired amount of flow to the re-heater 13 and also for cutting out the re-heater when desired.

The amount of elastic fluid re-heated varies of course with the requirements in any particular instance. In some cases a portion of the elastic fluid of the order of 10 to 20 per cent of the total may be re-heated, and while my invention is not limited to the re-heating of such a portion of the elastic fluid, it possesses particular advantage when the re-heating is limited to a relatively small percentage of the total.

In accordance with the provisions of the patent statutes, I have described the principle of operation of my invention, together with apparatus which I now consider to represent the best embodiment thereof, but I desire to have it understood that the apparatus disclosed is only illustrative, and that the invention may be carried out with such modifications as come within the scope of the appended claims.

What I claim as new and desire to secure by Letters Patent of the United States, is:—

1. The combination with an elastic fluid engine comprising a higher pressure portion, a lower pressure portion, and a main conduit through which elastic fluid flows from the higher pressure portion to the lower pressure portion, of re-heating means for imparting to a part of the elastic fluid flowing from the higher pressure portion to the lower pressure portion, the heat intended for reheating all such elastic fluid, branch conduit means connected to said main conduit for conveying a part of the elastic fluid from the main conduit through the re-heating means and back again to the main conduit, and means for effecting the flow through said branch conduit means.

2. The combination with an elastic fluid engine comprising a higher pressure portion, a lower pressure portion, and a main conduit through which elastic fluid flows from the higher pressure portion to the lower pressure portion, of re-heating means for imparting to a part of the elastic fluid flowing from the higher pressure portion to the lower pressure portion, the heat intended for reheating all such elastic fluid, branch conduit means connected to said main conduit for conveying a

part of the elastic fluid from the main conduit through the re-heating means and back again to the main conduit, and pump means in said branch conduit for effecting circulation through such conduit.

In witness whereof, I have hereunto set my hand this 8th day of June, 1926.
